TURBINE NOZZLE

Reinout P. Kroon, Swarthmore, and Charles A. Meyer, Drexel Hill, Pa., assignors to Westinghouse Electric & Manufacturing Company, East Pittsburgh, Pa., a corporation of Pennsylvania

Application March 8, 1941, Serial No. 382,321

3 Claims. (Cl. 253—78)

This invention relates to elastic-fluid turbine impulse stages and it has for an object to reduce shock of the moving blades.

We have found that, where a large proportion of the total turbine pressure drop occurs across the first partial peripheral admission impulse stage, the shock experienced by the moving blades leaving the zone of action of the last nozzle passage of a nozzle group is particularly severe, that is, the very large steam force acting across the blades is at that time suddenly removed. We have greatly reduced shock under these circumstances by restricting admission of steam to the last nozzle passage of the group, and it is a more particular object of the present invention to provide apparatus of this character and serving this purpose.

A further object of the invention is to provide a nozzle construction for an elastic-fluid turbine wherein the nozzles are arranged as adjacent primary and secondary groups with the final and initial nozzle passages thereof common to both groups.

These and other objects are effected by the invention as will be apparent from the following description and claims taken in connection with the accompanying drawing, forming a part of this application, in which:

Fig. 1 is a fragmentary developed sectional view of an impulse turbine stage having the improvement applied thereto;

Figs. 2, 3, 4 and 5 are views similar to Fig. 1 but showing alternative forms of the improvement;

Fig. 6 is a fragmentary side elevational view of the nozzles shown in Fig. 7;

Fig. 7 is a view similar to Fig. 1 and taken along the line VII—VII of Fig. 6; and

Fig. 8 is a transverse sectional view of the turbine stage shown in Fig. 7 and taken along the line VIII—VIII of Fig. 6.

In Fig. 1 there is shown an impulse stage, at 10, embodying stationary vanes or blades 11 and moving vanes 12, the stationary vanes providing nozzle passages 13 and 13a for supplying elastic fluid to the blade passages 12a.

As shown, the nozzle passages 13 are arranged in adjacent primary and secondary groups 14 and 15 supplied from adjacent nozzle chambers 16 and 17 and separated by an intermediate nozzle passage 13a.

With the conventional impulse stage, where the pressure drop across the moving blades is a large percentage of the initial pressure, the shock on the moving blades leaving a nozzle group or zone

is very pronounced. This shock may be reduced by limiting the supply of elastic fluid to the final nozzle passage of the group. Instead of the nozzle passages 13 being arranged as primary and secondary groups, at 14 and 15, and serving alone to supply elastic fluid separately from the nozzle chambers 16 and 17 to the blade passages, there is provided a nozzle passage 13a disposed intermediately of the groups and which communicates with adjacent ends of the chambers 16 and 17 to serve as a common nozzle passage for the latter. In other words, the passage 13a functions as the final nozzle passage with the primary nozzle group, at 14, and as the initial nozzle passage with the secondary nozzle group, at 15. Therefore, with steam supplied only to the primary nozzle chamber 16, flow therefrom through the nozzle passage 13a will be substantially less than through each of the nozzle passages 13 of the group at 14, and, in consequence, the shock on moving blades leaving the group will be reduced as compared to the usual arrangement where full flow occurs through the final nozzle passage. While it is inherent that flow through the nozzle passage 13a shall be less than through the passages 13 when steam is supplied only to the primary nozzle chamber 16, nevertheless, as steam is admitted to the secondary nozzle chamber 17 and such admission is progressively increased, the nozzle passage 13a becomes more and more effective until, with full steam admission to the secondary nozzle chamber, such passage is just about as effective as any of the nozzle passages 13.

In Fig. 1, the nozzle box or chamber partition 18 has its rear edge joined to the inlet edge 20 of the vane 11 separating the nozzle 13a from the adjacent nozzle passages 13 of the primary group, at 14, and elastic fluid is supplied to the nozzle passage 13a through a port 22 formed in the partition. As the partition 18 provides for substantial communication of the secondary nozzle chamber with the nozzle passage 13a, it will be apparent that such nozzle passage is common both to the primary and to the secondary nozzle chambers, it functioning as the final nozzle passage with the primary group, at 14, and as the initial nozzle passage with the secondary group, at 15.

Assuming the admission of steam only to the primary nozzle chamber 16, it will be apparent that the restricted communication thereof with the nozzle passage 13a assures of such limitation of flow through the latter that moving blades leaving the zone of action thereof will have shock

thereon substantially reduced as compared to the usual arrangement where full flow occurs through the final nozzle passage of the nozzle group. While the effectiveness of a nozzle passage 13a is reduced on this account as long as the steam supply is restricted to the primary nozzle chamber 16, just as soon as steam is admitted to the secondary nozzle chamber 17 and such admission is progressively increased, the common nozzle passage 13a for the adjacent primary and secondary nozzle groups becomes more and more effective until, with full steam admission to the secondary nozzle chamber 17, the nozzle passage 13a is just about as effective as any of the nozzle passages 13.

In Fig. 2, the structure is somewhat like that already described, the partition 18a is provided with an opening 22a inclined inwardly in the general direction of the initial passage 13a and formed in the junction region between the partition 18a and the inlet edge 20 of the nozzle vane 11.

In Fig. 3, the partition 18b is formed separately from the vanes 11, it constituting a part of the nozzle box chambers or structures 16 and 17 and defining passages 23 and 24 for supplying elastic fluid from the nozzle chambers 16 and 17 to the nozzle passage 13a.

In Fig. 4, the partition 18c has wall portions 25 arranged adjacent to the nozzle vanes 11, the partition structure having openings 26 and 27 for supplying elastic fluid from the primary and secondary nozzle groups to the common nozzle passage 13a for the adjacent nozzle groups 14 and 15.

In Figs. 6, 7, and 8, there is shown a further modified form of partition structure for the primary and secondary nozzle chambers. In these views, the primary nozzle chamber 16 has an outer portion 28 which overlaps radially an inner portion 29 of the secondary nozzle chamber 17, the partition structure comprising inner and outer wall elements 31 and 32 arranged adjacent to inlet edges of the vanes 11 and being joined by a circumferential element 33. The nozzle passage 13a has a circumferentially-extending partition 34 aligned with the partition 33 and dividing the nozzle passage 13b into inner and outer radial portions.

In Fig. 5, the partition 18d cooperates with a nozzle vane 11, as in Figs. 1 and 2, but, instead of providing an opening in the partition for supplying steam from the primary chamber to the nozzle passage 13a, the vane has an opening 36 for supplying steam to such nozzle passage.

While the invention has been shown in several forms, it will be obvious to those skilled in the art that it is not so limited, but is susceptible of various other changes and modifications without departing from the spirit thereof, and it is de-

sired, therefore, that only such limitations shall be placed thereupon as are specifically set forth in the appended claims.

What is claimed is:

5. In an elastic-fluid turbine, means providing circumferentially-adjacent primary and secondary nozzle chambers separated by a partition structure, a row of moving blades, and a plurality of vanes providing nozzle passages for discharging elastic fluid from the primary and secondary chambers to the blades, said partition structure cooperating with the vanes to divide the nozzle passages into primary and secondary groups separated by an intermediate nozzle passage with
- 10 the primary and secondary groups supplied with elastic fluid only from the primary and secondary nozzle chambers, respectively, and to provide entrance openings from both the primary and secondary nozzle chambers to the intermediate nozzle passage.
- 15 2. In an elastic-fluid turbine, means providing circumferentially-adjacent primary and secondary nozzle chambers separated by a partition structure, a row of moving blades, and a plurality of vanes providing nozzle passages for discharging elastic fluid from the primary and secondary chambers to the blades, said partition structure cooperating with the vanes to divide the nozzle passages into primary and secondary groups separated by an intermediate nozzle passage with the primary and secondary groups supplied with elastic fluid only from the primary and secondary nozzle chambers, respectively, and to provide entrance openings from both the primary and secondary nozzle chambers to the intermediate nozzle passage.
- 20 3. In an elastic-fluid turbine, means providing circumferentially-adjacent primary and secondary nozzle chambers separated by a partition structure, a row of moving blades, and a plurality of vanes providing nozzle passages for discharging elastic fluid from the primary and secondary chambers to the blades, said partition structure cooperating with the vanes to divide the nozzle passages into primary and secondary groups separated by an intermediate nozzle passage with the primary and secondary groups supplied with elastic fluid only from the primary and secondary nozzle chambers, respectively, and to provide entrance openings from both the primary and secondary nozzle chambers to the intermediate nozzle passage.
- 25 4. In an elastic-fluid turbine, means providing circumferentially-adjacent primary and secondary nozzle chambers separated by a partition structure, a row of moving blades, and a plurality of vanes providing nozzle passages for discharging elastic fluid from the primary and secondary chambers to the blades, said partition structure cooperating with the vanes to divide the nozzle passages into primary and secondary groups separated by an intermediate nozzle passage with the primary and secondary groups supplied with elastic fluid only from the primary and secondary nozzle chambers, respectively, and to provide entrance openings from both the primary and secondary nozzle chambers to the intermediate nozzle passage.
- 30 5. In an elastic-fluid turbine, means providing circumferentially-adjacent primary and secondary nozzle chambers separated by a partition structure, a row of moving blades, and a plurality of vanes providing nozzle passages for discharging elastic fluid from the primary and secondary chambers to the blades, said partition structure cooperating with the vanes to divide the nozzle passages into primary and secondary groups separated by an intermediate nozzle passage with the primary and secondary groups supplied with elastic fluid only from the primary and secondary nozzle chambers, respectively, and to provide entrance openings from both the primary and secondary nozzle chambers to the intermediate nozzle passage.
- 35 6. In an elastic-fluid turbine, means providing circumferentially-adjacent primary and secondary nozzle chambers separated by a partition structure, a row of moving blades, and a plurality of vanes providing nozzle passages for discharging elastic fluid from the primary and secondary chambers to the blades, said partition structure cooperating with the vanes to divide the nozzle passages into primary and secondary groups separated by an intermediate nozzle passage with the primary and secondary groups supplied with elastic fluid only from the primary and secondary nozzle chambers, respectively, and to provide entrance openings from both the primary and secondary nozzle chambers to the intermediate nozzle passage.

3. In an elastic-fluid turbine, means providing circumferentially-adjacent primary and secondary nozzle chambers separated by a partition structure, a row of moving blades, and a plurality of vanes providing nozzle passages for discharging elastic fluid from the primary and secondary chambers to the blades, said partition structure cooperating with the vanes to divide the nozzle passages into primary and secondary groups separated by an intermediate nozzle passage with the primary and secondary groups supplied with elastic fluid only from the primary and secondary nozzle chambers, respectively, and to provide entrance openings from both the primary and secondary nozzle chambers to the intermediate nozzle passage.
4. In an elastic-fluid turbine, means providing circumferentially-adjacent primary and secondary nozzle chambers separated by a partition structure, a row of moving blades, and a plurality of vanes providing nozzle passages for discharging elastic fluid from the primary and secondary chambers to the blades, said partition structure cooperating with the vanes to divide the nozzle passages into primary and secondary groups separated by an intermediate nozzle passage with the primary and secondary groups supplied with elastic fluid only from the primary and secondary nozzle chambers, respectively, and to provide entrance openings from both the primary and secondary nozzle chambers to the intermediate nozzle passage.
5. In an elastic-fluid turbine, means providing circumferentially-adjacent primary and secondary nozzle chambers separated by a partition structure, a row of moving blades, and a plurality of vanes providing nozzle passages for discharging elastic fluid from the primary and secondary chambers to the blades, said partition structure having an opening formed therein at the entrance of said intermediate nozzle passage for supplying elastic fluid from the primary nozzle chamber directly to such nozzle passage.
